UNITED STATES PATENT OFFICE

ANGUS F. HANNEY, OF CINCINNATI, OHIO, ASSIGNOR TO THE AMERICAN LAUNDRY MACHINERY COMPANY, OF CINCINNATI, OHIO, A CORPORATION OF OHIO

LAUNDRY MARKING TAG

Application filed June 10, 1927. Serial No. 197,896.

This invention relates to marking apparatus for use in conjunction with various kinds of treatment such, for example, as a laundry process.

5 More specifically, the invention relates to a laundry identifier or tag of a specific type wherein the main body portion is flat and forms one of the clamping members for securing the marker to the goods and is provided with a hinged clamping member preferably co-extensive with the clamping portion of the other member and adapted to be clamped and held upon the goods by a staple or other securing means.

10 15 Further details of the invention will be brought out in the following description, drawings and claim.

Referring to the drawings, Fig. 1 is a perspective view of the clamp open; Fig. 2 is a similar view showing the clamp applied; Fig. 3 is a longitudinal section; Fig. 4 is a perspective view of the staple; and Fig. 5 is a section across the waist of the marker.

In the arrangement shown, the identifier 20 25 comprises a main body portion 1 having suitable identifying recesses 2 and 3. Adjacent the main body portion 1 are suitable hinged portions 4 bent from the metal and connecting the main body portion with the back 30 35 clamping member 5. The clamping member is flat and is recessed on each side 6 to form a waist. Cooperating with the hinged portion 4 is a suitable hinge pin 7 passing through a suitable loop 8 forming a part of the outer identifier clamping member 9. This member is recessed on each side at 10 to form a waist. Engaging about these waists is a suitable holding device, in this instance, in the form of a staple 11 adapted to encircle the 40 45 waists of the clamping members and bent over upon the back after the article has been arranged between the outer ends of the clamping members.

What I claim is:

45 An identifier for marking apparatus comprising a pair of substantially flat members, one consisting of a body portion having a hinge part, identifying means, and a clamp portion having a waist, and the other member 50 comprising a clamping portion having a

waist and a hinge part at the end thereof, a pintle connecting the hinge parts and a staple surrounding said waists.

In testimony whereof I hereby affix my signature.

ANGUS F. HANNEY.
